UNITED STATES PATENT OFFICE.

BYERS W. KADEL, OF BALTIMORE, MARYLAND, ASSIGNOR TO THE SYMINGTON COMPANY, OF NEW YORK, N. Y., A CORPORATION OF MARYLAND.

JOURNAL-BOX LID.

Application filed February 25, 1926. Serial No. 90,669.

This invention relates to journal boxes and, more particularly, to a spring actuated lid therefor which has a spring so constructed that improper assembly thereof is prevented.

The principal object of my invention, generally considered, is the provision of a spring retainer for journal box lids so formed that it is impossible to assemble the same with 10 the lid and hinging member therefor in other than the correct position.

An object of my invention is the provision of a spring retainer formed with extensions which cooperate with the associated lid and 15 prevent improper assembly with respect thereto.

Another object of my invention is the provision of a retainer for stressing the spring of a spring actuated journal box lid provided 20 with flanges overlying the hinging portions of the lid so that it is impossible to assemble the retainer with respect thereto in inverted position.

A further object of my invention is the 25 provision of a spring retainer for spring actuated journal box lids formed with apertures for pivoting the same with respect to the journal box and lid and extensions adjacent said apertures which engage the adjacent portion of the lid and prevent alinement of the hinging apertures in the retainer and lid when the retainer is improperly assembled with respect thereto.

Other objects and advantages of the invention relating to the particular arrangement and combination of the various parts will 35 become apparent as the description proceeds.

Referring to the drawings illustrating my invention, the scope whereof is defined by 40 the appended claims:

Figure 1 is a side elevation of a journal box lid and an associated spring and retainer therefor embodying features of my invention.

45 Figure 2 is an end elevation of the lid, spring and spring retainer pivotally connected to an associated journal box.

Figure 3 is a view similar to Figure 2 but showing the retainer in release position 50 with respect to the spring.

Figure 4 is a partial sectional view on the line 4—4 of Figure 2.

Figure 5 is an end elevation of a modified form of spring retainer.

55 Referring to the drawings in detail, like

parts being designated by like reference characters, and considering first the modification of my invention illustrated in Figures 1 to 4, inclusive, a journal box 1 is shown provided with a hinge lug 2 formed with a cam-shaped surface 3 for a purpose to be hereinafter explained.

A lid 4 is hinged to the journal box 1 by means of a pintle or hinge pin 5 extending through the hinge lug 2 on the journal box. 60 The pintle may be held in position in any desired manner but, in the present instance, the lid is shown formed of sheet metal and the hinging portions or ears 6 are provided with tabs or tongues 8 which are bent over 65 with the ends of the hinge pin 5 for retaining the same in place. The lid, in the present instance, is shown reinforced by being embossed or corrugated, as indicated at 9.

For holding the lid in open or closed position, a double coil spring 10 is shown, the ends of which are secured to approximately the central portion of the lid 4 by means of a plate 11 connected to said lid by rivets or other securing means 12. Between the 75 coils 13 of the spring on a straight portion thereof is preferably mounted a roller or other anti-friction device 14 which is adapted to ride or roll on the cam-shaped surface 3 of the hinge lug 2 and hold the lid 80 in either open or closed position in a well known manner as will be understood. For placing the spring under initial tension, a spring retainer 15 is provided formed with a spring seat 16 adapted to engage the coils 85 13 of the spring and with hinging ears or portions 17 perforated for receiving the hinge pin or pintle 5 for pivotally connecting the lid and retainer with respect to the journal box 1. For assembling the parts in 90 the position shown in Figures 1 and 2, the pintle is first inserted through the registering apertures in the lid ears, the hinging lug, and the spring retainer, the parts being approximately in the position shown in Figure 95 3. The spring 10 is then placed under the desired initial tension by moving the retainer 15 downwardly about the hinge pintle 5 from the position shown in Figure 3 to that shown in Figure 2 where the spring 10 seating portion 16 overlies and engages the coils 13 of the spring 10 and places said spring under the desired initial tension.

It has been found that, in the past, some workmen are apt to assemble the retainer 110

with respect to the associated lid and journal box in improper or inverted position with the curved spring housing portion concave upwardly instead of downwardly. To 5 remedy such a possibility of improper assembly, I construct my spring retainer 15 with extensions 18 adapted to overlie the hinging ears on the lid with the distance between the outer edges of the extensions 18 10 greater than the distance between the inner edges of the ears 6 so that it is impossible to assemble the retainer with respect to the lid with the extensions or flanges 18 between the hinging lugs or ears 6 thereon or in any 15 other position than that shown in the drawings.

Referring to Figure 5, a modified form of 20 spring retainer 15^a is shown provided with a spring seating portion 16^a and hinging portions 17^a. In this embodiment of my invention, extensions 18^a are provided, which, instead of overlying the associated ears or hinging portions 6 of the lid, merely extend 25 radially outward for a distance greater than that between the hinging ears 6 and the cut-out portion 19 of the journal box lid so that 30 said retainer can only be assembled with respect to the lid with the extensions 18^a positioned away from the closure portion proper of the lid because, if positioned toward the closure portion of the lid, the 35 extensions 18^a would engage said lid at the cut-out portion 19 thereof and prevent alignment of the hinging apertures in the retainer with the hinging ears on the lid so that 40 assembly with respect thereto would be impossible.

By virtue of the foregoing, it will be apparent that I have devised a spring retainer 45 for journal box lids which is fool-proof in that it is impossible to assemble it incorrectly with respect thereto because, in accordance with one modification, the outstanding curved flanges would engage with the hinging ears on the journal box lid and, in the 50 other modification, the radially disposed extensions would engage with the closure portion proper of the lid if it were attempted to assemble the retainer with respect to the lid in other than correct position.

Having now described my invention, what I claim is:

1. In combination with a journal box having a lug with a cam surface, a hinged lid therefor, a spring one end of which is connected to the lid and another end of which engages the cam surface, and retainer means pivotally mounted with respect to the lid and engaging an intermediate portion of 55 said spring for stressing the same and holding it in assembled position, said means being formed with an outward extension preventing incorrect assembly thereof.

2. In combination with a journal box having a lug with a cam surface, a lid formed

with hinge ears, a hinge pintle extending through said ears and lug for pivoting said lid to the box, a spring one end of which is pivoted to the lid and the other end of which engages the cam surface on the lug, and retainer means pivoted on said pintle and adapted for being forced over an intermediate portion of said spring for stressing the same, said retainer means being extended outwardly for a distance sufficient to prevent 75 its being assembled incorrectly.

3. In combination with a journal box having a hinge lug formed with an exterior cam surface, a lid pivoted thereto by means of a hinge pin extending through said lug and hinge portions on the lid, a spring pivotally connected with an intermediate portion of said lid and formed with anti-friction means on the other end thereof, said anti-friction means engaging the cam surface on the lug, 85 and retainer means pivoted on said pin and adapted for rotation thereabout for engaging an intermediate portion of said spring to stress the same and hold it in assembled relation with respect to said lid for holding the 90 lid in open or closed position, said retainer being provided with extensions adjacent the hinge portions on the lid for preventing incorrect assembly thereof by engaging said lid when applied in any position but the correct one.

4. In combination with a journal box having a hinge lug formed with an exterior cam surface, a lid pivoted to said lug by a pintle extending through hinge portions thereof and said hinge lug, a double coil torsion spring with an end portion thereof pivotally connected to a central portion of the lid and another end portion with an anti-friction roller thereon engaging the cam surface on the 100 lug, and retainer means pivotally connected with respect to said box and formed with a housing portion adapted for engaging the coil portions on the spring for stressing said 105 spring and holding the same in position, the pivoted portions of said retainer being formed with extensions which engage adjacent portions of the lid if it is attempted to apply the same incorrectly with respect thereto.

5. In combination with a journal box having a hinge lug formed with a cam surface thereon, a hinged lid therefor, a spring one end of which is connected to the lid and the opposite end of which engages the cam surface for holding the lid in open or closed positions, and retainer means adapted to engage an intermediate portion of the spring for applying the desired initial stress thereto and holding it in assembled position, said 120 retainer means being hinged adjacent the hinged portions of the lid and formed with flanges normally overlying said hinged portions of the lid for preventing incorrect assembly therewith.

6. In combination with a journal box, a lug thereon formed with a cam surface, a lid formed with hinging portions, a hinge pin extending through said hinging portions and lug for pivotally connecting said lid and box, a spring one end of which is pivotally connected with respect to the lid and the other end of which cooperates with the cam surface on the lug for holding the lid in open or closed positions, and spring retainer means pivoted on said pin and adapted for rotation thereabout to engage an intermediate portion of the spring and stress the same, said retainer means being formed with flanges extending outwardly over the adjacent hinging portions on the lid for preventing insertion of said flange portions therebetween and incorrect assembly with respect thereto.
- 10 7. In combination with a journal box having a hinge lug formed on the exterior thereof with a cam surface, a lid pivoted thereto by means of a hinge pin extending through the hinge lug and registering hinge portions on the lid, a spring pivotally connected to an intermediate portion of said lid and formed with anti-friction means on another portion thereof, said anti-friction means being adapted for engagement with the cam surface on the lug, and retainer means pivoted on said pin and adapted for rotation thereabout for engaging an intermediate portion of said spring to stress the same and hold it in assembled relation with respect to said lid for causing engagement of said anti-friction means with the cam surface on the lug to hold the lid in open or closed position, said retainer being formed with flanges extending outwardly and overlying adjacent portions of the hinging portions on the lid for preventing incorrect assembly with respect thereto.
- 15 8. In combination with a journal box having a hinge lug formed with an exterior cam surface, a lid pivotally connected to said lug by a pintle extending through hinge portions thereof and said hinge lug, a double coil torsion spring with an end portion thereof pivotally connected to a central portion of the lid and another end portion with an anti-friction roller pivotally connected thereon and adapted for engagement with the cam surface on the lug, and retainer means pivotally connected with respect to said portion and formed with a curved portion adapted for engaging and seating the coil portions of the spring for stressing said spring and holding the roller thereon in resilient engagement with the cam surface on the lug, the pivoted portions of said retainer being formed with angular extensions overlying adjacent hinge portions of the lid but spaced therefrom when correctly assembled with respect thereto, said angular portions being adapted for preventing incorrect assembly of the retainer.
- 20 9. A spring retainer formed with a portion adapted to engage and stress an intermediate portion of a journal box lid spring and another portion perforated for pivotal engagement with respect to a journal box and lid pivoted thereto, said perforated portion lying adjacent the pivoted portions of the lid and formed with an extension preventing incorrect assembly with respect to said lid by engaging said portions of the lid and preventing alinement of the hinging apertures when incorrectly positioned.
- 25 10. A spring retainer for journal box lid springs comprising a curved portion adapted for engaging and stressing an intermediate curved portion of a spring and perforated ears extending therefrom and adapted for pivotal connection with respect to the hinging element between the lid and journal box, said ears being formed with flanges adapted to normally overlie the adjacent hinging portions on the lid, said flanges serving to prevent incorrect assembly of the spring retainer between the hinge portions of the lid.
- 30 45 In testimony whereof I affix my signature.
